UNITED STATES PATENT OFFICE.

ZOLTAN MOLNAR, OF PORT ROBINSON, ONTARIO, CANADA, ASSIGNOR OF ONE-FOURTH
TO MIHALY SZABO CZORBOY AND ONE-FOURTH TO HORACE A. FIFIeld, BOTH OF
WELLAND, ONTARIO, CANADA.

RAIL-SWITCH-LOCKING DEVICE.

Application filed September 17, 1926. Serial No. 136,085.

This invention relates generally to locking devices, and has more particular reference to a novel type of locking device for railway switches.

5 The invention has for an object the provision of an improved locking device for switch points, which will be exact and efficient in operation.

10 For further comprehension of the invention, and of the objects and advantages thereof, reference will be had to the following description and accompanying drawings, and to the appended claims in which the various novel features of the invention 15 are more particularly set forth.

Referring to the drawings forming a material part of this disclosure:

20 Fig. 1 is a side elevational view of a device constructed according to this invention, said device being applied to a pair of rails and point-rails, shown in section.

Fig. 2 is a plan elevational view thereof.

25 Fig. 3 is a vertical sectional view taken on the line 3—3 of Fig. 2.

Fig. 4 is a fragmentary, partly sectional detail view of certain parts.

30 Fig. 5 is a fragmentary enlarged plan view, with the cover of the locking chamber removed.

Fig. 6 is an enlarged fragmentary central vertical sectional view of the device, certain parts being shown full and others in section.

35 The reference numeral 10 indicates a pair of rails, and the numerals 11 indicate co-acting point-rails of a switch. The rails 10 are held down in a customary manner to the roadbed, and the point-rails 11 switch to right or left by customary switching mechanism not shown on the drawings. The invention device locks the point-rails either to the right or left, so that the said customary switching mechanism cannot move the point-rails, either to the right or left 45 while thus locked.

40 Clamp member 12 has a projecting tongue 12^a engaged over the base of the rails 10, and an extension 12^b beneath the rail, formed with serrations on the upper face thereof.

50 The rail clamp 13 has serrations on its bottom face, co-actable with the serrations on said extension 12^b, and grips over the other sides of the bases of rails 10. The clamp rails are held in position by stud and

nuts 14, said nuts being formed with several 55 apertures 14^a, and a rod 15 engages in one of said apertures to lock the nut in position.

The clamp member 12 on the right hand side of the drawings has a lead head 16 60 fastened thereto by means of bolts 17. One end of the rod 15 is shown secured to the bottom end of one of the bolts 17. The clamp member 12 on the left hand side of the drawings has a casing 18 formed with a 65 projecting lead head 19 fastened thereto by means of bolts 20. One end of the rod 15 is shown secured to the bottom end of one of the bolts 20. The casing 18 is formed by an upper and lower part held together 70 by the bolts 20 clamping projecting bosses 18^a, 18^b from the upper and lower parts respectively, and pivoted clamps 21 from the upper part engaging a latch 22 from the lower part.

75 Rotatively mounted in lead head 16 is a long locking rod 23, which also projects rotatively into casing 18. Similarly a short locking rod 24 rotatively projects from the other side of casing 18. The outer ends of 80 these locking rods are formed with latch pieces 25 having straight extensions 25^a, and heel formed pieces 25^b. The latch piece 25 on the right hand side of the drawings is turned with its heel formed piece 25^b upwards, abutting the inner side of the point-rail 11, while the latch piece 25 on the left hand side of the drawings is turned with its straight extension 25^a upwards, abutting the inner side of the point-rail 11. The 90 inner end of short locking rod 24 is formed with a groove 24^a, engageable by a tongue 23^a formed on the inner end of long locking rod 23 to hold these rods in relative 95 positions. A nut 27 threadedly engages the ends of these rods to fasten them in longitudinally adjusted positions. The nut 27 is formed with external teeth 27^a, capable of meshing with a gear segment 28 engaged to a rod 29, and pivoted as at 30 to a bracket 100 31, fastened on top of casing 18. The bracket 31 is formed with a groove 31^a in which a slide 32 operates.

105 The long locking rod 23 has formed thereon an enlarged portion 33, having front projecting arms 34 between which a handle 35 is pivotally fastened. The casing 18 has depending lugs 36, and the handle 35 may be

swung parallel to the rod 23, so that the bottom of the handle engages between these lugs to lock the rod in certain positions. The inner side of enlarged portion 33 is 5 formed with a circular flange 33^a having a piece cut off so as to form a straight edge, indicated in the drawings at 33^b by the side projecting less than the other side.

Within the casing 18 are two locks, one on 10 each side of the locking rods. The key for the lock may be inserted through keyhole 40', and latch members 41 suitably connected with the end member 42 may be pushed back so that the end member engages against the 15 straight edge 33^b preventing a turning of the locking rods 23, 24. The latch members 41 are formed with slots 41^a through which screws 43 are guided allowing certain movements of the latch member. A support 44 20 is secured by screws 43 to the casing 18, and is provided with projecting pins 45. Springs 46 are welded against the bottom of the top pins 45, and press downward on top of the latch members 41 to frictionally hold the 25 latch members in various positions as moved by the key, the latch members being only laterally slideable due to screws 43 and slots 41^a. A suitable key may be inserted through the key holes 40' using the bottom pins 45 as 30 a pivot point, and the latch members 41 are cut out as indicated at 41' so that the key may slide the group of latch members together with the end members 42 backwards and forwards into and out of locking position. The latch members 41 and the end 35 members 42 are held against lateral displacement since they slide between the supports 44 and the side of the casing 18, the end members 42 being provided with side members 42' for this purpose. The side members 42' are provided with end extensions 42^a 40 formed with slots 40 having a central bulge 40^b. The flats 40^c of screws 40^d engage in the slots 40 and these flats are of greater 45 length than the width of the slots so that the screws cannot be turned unless the key inserted in keyhole 40' is partly turned to move the end extensions 42^a slightly so that the flats 40^c are turnable in the bulges 40^b. In 50 Figure 5 one of the screws 40^d is shown in section below the flat 40^c, while the other is shown in section through the flat 40^c, though both screws have the flats. These screws 40^d serve to hold the top and bottom 55 of casing 18 together in conjunction with latch 22. An unauthorized person cannot open the casing to tamper with the locks therein, since the same key which controls the locks is necessary to adjust end extensions 42^a so that the bulges 40^b permit the flats 40^c to turn.

As shown in Fig. 1 the rail-points 11 are locked to the left. The handle 35 may be 60 swung so that the latch pieces are in a horizontal position. Then the rail-points 11 may

be operated to the right, thereafter the handle 35 further swung so that the heel formed piece 25^b on the left hand side of the drawings engages against the outer side of the rail-point, while the straight extension 25^a 65 on the right hand side of the drawings engages against the inner side of the rail-point. Referring to Fig. 5, and looking towards the bolts 20, the lock on the right side locks the latch pieces 25 as shown in Fig. 1, while if 70 the latch pieces 25 are turned and the switch rail-points thrown to the right, thereafter the latch pieces 25 further turned to engage the rail-points, the flat portion 33^b will now be on the left, and the left lock may be used 75 to lock the parts. The distance between the latch pieces 25 may be adjusted by the proper manipulation of handle 29. Disengage 23 from 24, by manipulating handle 29 so that nut 27 moves onto rod 24, make the 80 proper adjustment, and then reengage these parts. This manipulation of handle 29 consists in placing the handle on one side and so that segment 28 engages nut teeth 27^a, 85 and then moving the handle to the other side. Thereafter removing the handle and reengaging it in its former position, and again moving it, and so on until the nut 27 is 90 moved onto rod 24, and free from rod tongue 23^a. During the manipulation of handle 29, 95 slide 32 is used to remove the handle from the pivot point in order to obtain a proper setting each time. The caretaker of the invention device normally keeps the rod 29 and segment 28 in his tool kit. The device is 100 operated without these parts. Only at a time when the caretaker is adjusting the distance between the latch pieces are the said parts applied to the device.

While I have illustrated and described my 105 invention with some degree of particularity, I realize that in practice various alterations therein may be made. I therefore reserve the right and privilege of changing the form of the details of construction or otherwise 110 altering the arrangement of the correlated parts without departing from the spirit or the scope of the appended claims.

Having thus described my invention, what 115 I claim as new and desire to secure by United States Letters Patent is:

1. A lock for railway switch points, comprising clamp members engaged to the rails associated with said switch points, a lead head fixed to one of said clamp members, a casing with a projecting lead head fixed to the other of said clamp members, a long and a short locking rod rotatively mounted in said lead heads and casing, said rods being interengaged within the casing by a nut 120 threadedly engaging over a groove in one rod and a tongue in the other rod, the outer ends of said rods being formed with latch pieces engageable with the inner and outer sides of said switch points, means for turn- 125 130

ing said locking rods and means for preventing the turning of said locking rods.

2. A lock for railway switch points, comprising clamp members engaged to the rails associated with said switch points, said clamp members being formed with end rail clamps, a lead head fixed to one of said clamp members, a casing with a projecting lead head fixed to the other of said clamp members, a long and a short locking rod rotatively mounted in said lead heads and casing, said rods being interengaged within the casing by a nut threadedly engaging over a groove in one rod and a tongue in the other rod, the outer ends of said rods being formed with latch pieces engageable with the inner and outer sides of said switch points, means for turning said locking rods and means for preventing the turning of said locking rods.

3. A lock for railway switch points, comprising clamp members engaged to the rails associated with said switch points, a lead head fixed to one of said clamp members, a casing with a projecting lead head fixed to the other of said clamp members, a long and a short locking rod rotatively mounted in said lead heads and casing, said rods being interengaged within the casing by a nut threadedly engaging over a groove in one rod and a tongue in the other rod, the outer ends of said rods being formed with latch pieces engageable with the inner and outer sides of said switch points, means for turning said locking rods, said means comprising an enlarged portion fixed to said locking rod, brackets depending from said enlarged portion, and a handle pivotally mounted between said brackets, and means for preventing the turning of said locking rods.

4. A lock for railway switch points, comprising clamp members engaged to the rails associated with said switch points, a lead head fixed to one of said clamp members, a casing with a projecting lead head fixed to the other of said clamp members, a long and a short locking rod rotatively mounted in said lead heads and casing, said rods being interengaged within the casing by a nut threadedly engaging over a groove in one rod and a tongue in the other rod, the outer ends of said rods being formed with latch pieces engageable with the inner and outer sides of said switch points, means for turning said locking rods, said means comprising an enlarged portion fixed to said locking rod, brackets depending from said enlarged portion, and a handle pivotally mounted between said brackets, the said casing being formed with lugs and the bottom of said handle being engageable between said lugs, and means for preventing the turning of said locking rods.

5. A lock for railway switch points, com-

prising clamp members engaged to the rails associated with said switch points, a lead head fixed to one of said clamp members, a casing with a projecting lead head fixed to the other of said clamp members, a long and a short locking rod rotatively mounted in said lead heads and casing, said rods being interengaged within the casing by a nut threadedly engaging over a groove in one rod and a tongue in the other rod, the outer ends of said rods being formed with latch pieces engageable with the inner and outer sides of said switch points, means for turning said locking rods and means for preventing the turning of said locking rods, said latter means comprising an enlarged portion fixed to said locking rod, a flange on the inner side of said portion, said flange being cut straight on one side, and a lock having slidable members engageable against said cut straight side.

6. A lock for railway switch points, comprising clamp members engaged to the rails associated with said switch points, a lead head fixed to one of said clamp members, a casing with a projecting lead head fixed to the other of said clamp members, a long and a short locking rod rotatively mounted in said lead heads and casing, said rods being interengaged within the casing by a nut threadedly engaging over a groove in one rod and a tongue in the other rod, a means for adjusting said nut, the outer ends of said rods being formed with latch pieces engageable with the inner and outer sides of said switch points, means for turning said locking rods, and means for preventing the turning of said locking rods.

7. A lock for railway switch points, comprising clamp members engaged to the rails associated with said switch points, a lead head fixed to one of said clamp members, a casing with a projecting lead head fixed to the other of said clamp members, a long and a short locking rod rotatively mounted in said lead heads and casing, said rods being interengaged within the casing by a nut threadedly engaging over a groove in one rod and a tongue in the other rod, a means for adjusting said nut, said means comprising a gear segment and a handle removably and pivotally mounted to said casing, and said nut being formed with external gear teeth engageable with said gear segment, the outer ends of said rods being formed with latch pieces engageable with the inner and outer sides of said switch points, means for turning said locking rods, and means for preventing the turning of said locking rods.

8. A lock for railway switch points, comprising clamp members engaged to the rails associated with said switch points, a lead head fixed to one of said clamp members, a casing with a projecting lead head fixed to

the other of said clamp members, a long and a short locking rod rotatively mounted in said lead heads and casing, said rods being interengaged within the casing by a nut 5 threadedly engaging over a groove in one rod and a tongue in the other rod, a means for adjusting said nut, said means comprising a gear segment and a handle removably and pivotally mounted to said casing by means 10 of a bracket attached to said casing, said bracket being formed with a groove, and a

slide in said groove, and said nut being formed with external gear teeth engageable with said gear segment, the outer ends of said rods being formed with latch pieces engageable with the inner and outer sides of said switch points, means for turning said locking rods, and means for preventing the turning of said locking rods. 15

In testimony whereof I have affixed my 20
signature.

ZOLTAN MOLNAR.
